UNITED STATES PATENT OFFICE

ARTHUR H. SCHLOZ, OF TOLEDO, OHIO, ASSIGNOR TO THE TOLEDO MACHINE & TOOL COMPANY, OF TOLEDO, OHIO, A CORPORATION OF OHIO

METAL-STAMPING PRESS

Application filed September 17, 1928. Serial No. 306,590.

This invention relates to metal stamping presses of the type having a crank-operated slide, to which the movable die is secured, and objects of this invention are to provide a simple and efficient guide for the reciprocable slide, which is adapted to maintain accurate alignment of the slide with respect to the work support, and is so constructed as to prevent turning or twisting of the slide with respect to the machine frame; and to provide means for guiding the movement of the slide having increased bearing surface, and is adapted to offer resistance to pressure resulting from the angularity of the crank and connections near the bottom of the working stroke. Other objects and advantages will hereinafter appear.

The invention is shown by way of illustration in the accompanying drawings, in which:

Fig. 1 is a side elevation of a press embodying the improved construction; and

Fig. 2 is a transverse sectional view on the line 2—2 on Fig. 1.

The illustrated embodiment of the invention comprises a press having an upright frame 1, adjacent the upper portion of which is crank shaft 2 provided with a fly wheel 3. The crank shaft 2 is provided with a central crank which is connected to a vertically reciprocable slide 4 by a connecting rod 5. The machine frame is provided intermediate its upper and lower extremities with a recess 6, in which the slide 4 is movable, and a bolster plate 7 constitutes a work support, on which the stationary die is mounted, it being understood that the movable die is suitably secured to the slide 4 in the usual manner.

In accordance with this invention longitudinal extending guide elements 8 are secured by bolts 9 to the side walls of the recess 6, and these elements are wedge-shaped with the inclined or tapering surfaces extending inwardly toward the slide 4. The opposite sides of the slide 4 are formed with substantially V-shaped channels or grooves 10 to receive the tapering sides of the guide elements 8.

It is manifest that with this arrangement

more accurate alignment of the slide 4 is effected with respect to the work support, and any tendency of the slide to twist or turn is overcome. A further advantage of this arrangement resides in the fact that the oppositely tapering surfaces offer increased resistance to side pressures exerted on the slide by the connecting rod 5 in the angular positions assumed by the latter.

As indicated at 11, a portion of the slide 4 also has bearing on the inner wall of the recess 6, so that the frame also provides a bearing for the slide. This offers additional resistance to the pressure exerted upon the slide due to the angularity of the crank and connecting rod 5 above the bottom of the working stroke. It will be seen that near the inner wall of the recess 6 the slide not only has bearing on the frame, but also an inclined bearing in the bearing element 8 so that the bearing surface of the slide is materially increased.

Engaging the outer edge portion of the frame 1 adjacent the bearing elements 8 are gibs 12, which are securely held in position by bolts 13. These gibs overlap the bearing elements 8 and securely retain the latter in position. The gibs 12 are connected by tie plates 14, which, as shown, are integral with the gibs. The tie plates 14 hold the gibs together and reduce the side play caused by relatively great side pressure.

It will be seen that I have provided an exceedingly simple and efficient guide for the slide, which not only resists the tendency of the slide to turn, but also increases the bearing surface for the guides, and distributes the pressure exerted on the slide by the crank and connections. By this arrangement the slide is maintained in accurate alignment with the work support throughout its working stroke.

As shown, engaging one of the bearing elements 8 are adjusting screws 15 for properly positioning the bearings and compensating for wear. In this manner, by simple adjustment, the alignment of the guide may be secured at all times.

It is to be understood that numerous changes in details of construction and ar-

angement may be effected without departing from the spirit of the invention, especially as defined in the appended claims.

What I claim as new and desire to secure by Letters Patent is:

- 5 1. In a press of the character described, a frame, a crank-operated slide reciprocable in said frame, a bearing on the frame for a portion of one side of said slide, a substantially V-shaped channel in opposite sides of said slide, wedge-shaped guide members for said channels, a gib on each side of the frame engaging the adjacent guide member for retaining the latter in place.
- 10 2. In a press of the character described, a frame, a slide reciprocable in said frame having channels in opposite sides, substantially wedge-shaped bearing elements on opposite sides of said slide projecting into said channels, bearings on said frame adjacent said elements, gibs on the opposite side of said bearing elements, and a tie plate connecting said gibs for reducing the side play caused by relatively great side pressure on the bearings.
- 15 3. In a press of the character described, a frame, a slide reciprocable in said frame having channels in opposite sides, substantially wedge-shaped bearing elements on opposite sides of said slide projecting into said channels, means for detachably connecting said bearing elements to said frame, bearings on said frame adjacent said elements, gibs on the opposite side of said bearing elements, and a tie plate connecting said gibs and integral therewith for reducing the side play caused by relatively great side pressure on the bearings.
- 20 4. In a press of the character described, a frame, a slide reciprocable in said frame and having channels at opposite sides, bearing elements having a wedge fit in said channels, means for adjusting the distance between said bearing elements to compensate for wear, bearings on said frame adjacent said elements, gibs secured to the frame and projecting over the opposite sides of said bearing elements, and a tie plate connecting said gibs.
- 25 5. In a press of the character described, a frame, a slide reciprocable in said frame having substantially V-shaped channels at opposite sides thereof, a portion of said slide adjacent each of said V-shaped channels bearing against an adjacent part of said frame, and a longitudinally disposed wedge shaped guide member mounted on opposite sides of said frame adjacent said frame-bearing portions of said slide and fitting the opposite inclined sides respectively of said channels, whereby each side of said slide bears respectively against the opposite inclined sides of a guide member and a part of the frame.

In testimony whereof I have hereunto signed my name to this specification.

ARTHUR H. SCHLOZ.
